CLAIM

The ornamental design for a face mask, as shown and described.

DESCRIPTION

FIG. 1 is a left side perspective view of a first embodiment of a face mask, shown in an in-use configuration in an environment of use, showing our new design;

FIG. 2 is another left side perspective view thereof, shown in an in-use configuration;

FIG. 3 is a front view thereof;

FIG. 4 is a left side view thereof;

FIG. 5 is a rear view thereof;

FIG. 6 is a top view thereof;

FIG. 7 is a bottom view thereof;

FIG. 8 is front view thereof, shown in an unused configuration;

FIG. 9 is a rear view thereof;

FIG. 10. is front view of a second embodiment of a face mask shown in an unused configuration;

FIG. 11 is a rear view thereof;

FIG. 12 is front view of a third embodiment of a face mask shown in an unused configuration;

FIG. 13 is a rear view thereof;

FIG. 14 is front view of a fourth embodiment of a face mask shown in an unused configuration;

FIG. 15 is a rear view thereof;

FIG. 16 is front view of a fifth embodiment of a face mask shown in an unused configuration;

FIG. 17 is a rear view thereof;

FIG. 18 is a front view of a sixth embodiment of the face mask shown in an unused configuration; and,

FIG. 19 is a rear view thereof.

The broken lines illustrate welding or stitching on the face mask and do form part of the claimed design. The dash-dot lines in FIG. 1 represent the environment of a wearer's head.
